UNITED STATES PATENT OFFICE.

WILLARD F. RICHARDS, OF BUFFALO, NEW YORK, ASSIGNOR TO GOULD COUPLER COMPANY,
OF NEW YORK, N. Y.

CAR-COUPING

No. 894,534.

Specification of Letters Patent.

Patented July 28, 1908.

Application filed December 6, 1906. Serial No. 346,640.

To all whom it may concern:

Be it known that I, WILLARD F. RICHARDS, a citizen of the United States, residing at Buffalo, in the county of Erie and State of New York, have invented a new and useful Improvement in Car-Couplers, of which the following is a specification.

This invention relates more particularly to car couplers of the Master Car Builders' type, which have a horizontally-swinging knuckle, a lock for holding the knuckle closed or in position to hold the co-operating coupler, means for operating the lock to release the knuckle, and a kicker or device, also actuated by the lock-operating means, for swinging the knuckle open when released, ready for coupling with another coupler.

The object of the invention is to produce an efficient and desirable coupler composed of the minimum number of parts which are constructed and arranged to the best advantage for simplicity and strength and can be economically manufactured and assembled.

In the accompanying drawings, consisting of two sheets: Figure 1 is a side elevation, partly in section, in line 1—1, Fig. 2, of a car coupler embodying the invention. Fig. 2 is a horizontal sectional plan thereof in line 2—2, Fig. 1. Fig. 3 is a fragmentary sectional elevation in line 3—3, Fig. 2, showing the lock and kicker lever. Fig. 4 is a transverse sectional elevation of the coupler, on an enlarged scale, in line 4—4, Fig. 2. Fig. 5 is a front elevation thereof, on an enlarged scale, the knuckle being removed.

Like letters of reference refer to like parts in the several figures.

A represents the coupler head, and B the knuckle which, as usual, is pivoted to one side of the head, by a vertical pin b, or other ordinary means, and is provided with the usual tail b' adapted to extend into the head to engage the lock C. The knuckle, and coupler head also, except as hereinafter specified, may be of any usual or suitable construction.

The lock, which slides horizontally forwardly and rearwardly in the head into and out of locking engagement with the tail of the knuckle, bears against the longitudinal side wall c of the head and has top and bottom longitudinal guide projections c', Figs. 1 and 5, which engage and slide between said side wall and opposite parallel ribs c² c³ ex-

tending inwardly from the top and bottom of the head, by which, together with a stem c⁴ extending rearwardly from the lock through a hole in a lug c⁵ in the head, the lock is guided. A spring d surrounds the lock stem 60 between the body of the lock and the guide lug c⁵ for throwing the lock forwardly into locking position between the side wall c of the head and the tail of the knuckle, as shown in Fig. 2. In coupling, the tail of the knuckle 65 strikes the lock moving it rearwardly, and when it passes the lock, the latter is thrown forwardly by its spring and locks the knuckle. The lock can be readily slipped into place in the head through an opening e, see Fig. 5, in 70 the front wall of the head.

F represents a lever for operating the lock. This lever is arranged outside of the head at the side adjacent to the lock and is pivoted in any suitable way to swing horizontally, 75 for instance, the lever is located between two of the usual exterior strengthening ribs of the head and fulcrumed on a vertical pivot pin f passing through holes in said ribs and the lever. One end of the lever projects through a hole f' in the side wall c of the head into a recess f² in the lock, so that by swinging the outer end of the lever forwardly its inner end will shove the lock rearwardly against the action of its spring, beyond the tail of the 80 knuckle to release the knuckle. The forward swing of the inner end of the operating lever is limited by the engagement thereof with the front edge of the hole f' through which the lever enters the head, so that the 85 lever constitutes a stop to limit the forward movement of the lock and prevent its displacement or removal from the head except by first detaching and withdrawing the operating lever. The operating lever can be 90 connected to any usual actuating means (not shown).

G represents the kicker or knuckle-opening lever. This is arranged in the head in rear of the tail of the knuckle. It is pivoted centrally on a suitable vertical pivot or pin g in the head to swing horizontally, with one end bearing against the tail of the knuckle while the other end projects toward the lock, terminating in rear of a lateral shoulder g' 100 thereon so located at or near the front end of the adjacent side of the lock that it will not strike the kicker lever until the lock has been moved rearwardly far enough to clear the 105 tail of the knuckle, but will then engage the 110

kicker lever and under the continued rearward movement of the lock by its operating lever will swing the kicker lever and open the knuckle.

5. A spring-actuated lock sliding longitudinally in the head to lock and release the knuckle, and a kicker lever operating to open the knuckle are not new, but the described construction of the lock and relative arrangement of the same with the kicker lever and the operating lever, which also forms a stop for the lock, is novel and makes a very simple and desirable construction. All of the parts are located compactly in the head of the 10 coupler and there are no connecting links, pins or other small and frail parts which can be readily broken or get out of order.

I claim as my invention:

1. In a car coupler, the combination of a 15 head, a knuckle, a knuckle lock arranged to slide in the head, a lock-operating lever pivoted exteriorly on the head at one side of the lock with one end extending through a hole in the wall of the head in front of a portion of

the lock, and a kicker lever fulcrumed in the 20 head at the opposite side of the lock with one end arranged to bear against the knuckle and the other end in rear of a portion of the lock to be engaged thereby, substantially as set forth.

2. In a car coupler, the combination of a 25 head, a knuckle, a knuckle lock arranged in the head against one side wall thereof, said lock having top and bottom guide projections, and upper and lower ribs in said head 30 between which and said side wall said projections on the lock engage to guide the lock, the front wall of the head having a hole through which the lock can be inserted into the head, and means for operating the lock, 35 substantially as set forth.

Witness my hand, this 28th day of November, 1906.

WILLARD F. RICHARDS.
